UNITED STATES PATENT OFFICE.

JACK GERBERHOLTZ, OF BROOKLYN, NEW YORK.

DESIGN FOR A GAME BOARD.

Application filed July 12, 1923. Serial No. 6,761. Term of patent 3½ years.

To all whom it may concern:

Be it known that I, JACK GERBERHOLTZ, a native of Russia, having declared my intentions of becoming a citizen of the United States, residing in the borough of Brooklyn, county of Kings, city and State of New York, have invented a new, original, and ornamental Design for a Game Board, of which the following is a specification, reference being had to the accompanying drawing, forming part thereof.

The figure is a plan view of a game board, showing my new design. The shade lines represent symbolically, according to rules, the colors blue and red.

I claim:—

The ornamental design for a game board, as shown and described.

JACK GERBERHOLTZ.
